UNITED STATES PATENT OFFICE

KENNETH C. D. HICKMAN, OF ROCHESTER, NEW YORK, ASSIGNOR TO EASTMAN KODAK COMPANY, OF ROCHESTER, NEW YORK, A CORPORATION OF NEW YORK

PROCESS AND APPARATUS FOR REGULATING CHEMICAL REACTIONS

Application filed August 1, 1927. Serial No. 209,807.

This invention relates to processes and apparatus for regulating chemical reactions. It finds its present field of greatest usefulness in regulating the titration of streams of reagents automatically. One object of the invention is to provide a process in which a conductivity measurement, made upon an electrolyte separate from the reaction ingredients, indicates whether or not a definite stage of the reaction has been reached. Another object of the invention is to utilize the presence of a gas at the reaction mixture to indicate the stage of the reaction by altering the conductivity of a separate electrolytic cell. Still another object of the invention is to provide a process and apparatus in which streams of reagents are titrated against each other and any excess flow of a stream is automatically corrected, the presence or absence of gas from the reaction mixture altering the conductivity of a separate electrolytic cell, and the latter controlling the flow of one of the streams relative to the others,—in other words, the cell acts as an "electrolytic nose" to examine the condition of the reaction mixture by "smelling" the gas evolved. Still another object is to provide such an apparatus and process in which the electrolyte in the cell is continuously changed so that successive amounts of gas from the reaction mixture will pass into separate portions of electrolyte. Other objects will hereinafter appear.

In the accompanying drawing,—

Fig. 1 is a diagrammatic sectional view illustrating one form of apparatus in which my invention may be embodied and carried out;

Fig. 2 is a side elevation of a stream regulator which is readily controlled.

In conducting chemical reactions, especially those in which one liquid is titrated against others, the presence or absence of an excess of said liquid has been customarily indicated by a color indicator. In some instances electrical conductivity measurements have been made, but so far as I am aware, these have been made directly upon the reaction mixture of the liquids. For many types of reactions, and especially where exact control is essen-

tial, such measurements on the reaction mixture are troublesome and subject to error.

In contradistinction to such measurements on the reaction mixture, which may be called internal indications, I employ an external indicator, and measure the conductivity of an electrolyte in a cell separate from the reaction mixture and into which any gas from the reaction mixture passes. It is, therefore, essential in my process that one of the reagents, or else the product of the reaction, shall contain a volatile or gaseous material which, when dissolved in the electrolyte of the cell, will display a characteristic conductivity. It is convenient to conduct any such gas or vapor from the reaction mixture to the electrolyte in the indicator cell by means of a current of air or inert gas.

There are many reactions to which my process and apparatus may be applied. Typical of the reactions in which one of the reagents contains a volatile gas is the following:

An aqueous solution of sulfuric acid is mixed with ammonia water. If the ammonia water is run into the sulfuric acid there will be no gas present in the reaction mixture, as long as the sulfuric acid is in excess. But when the reaction reaches the stage where the sulfuric acid is wholly neutralized, further addition of ammonia water will provide an amount of free ammonia gas at the reaction mixture. If this gas be conducted, such as by a stream of air, into an electrolytic cell containing an aqueous electrolyte, including even plain water, it will greatly increase the conductivity of said electrolyte, and thus show that the reaction has reached the neutralization stage. It is preferable to pass a stream of air continually in contact with the reaction mixture and through the electrolyte into the detection cell, so that the latter will, by its increased conductivity, show instantly when the first amount of ammonia is given off.

Instead of pouring one ingredient gradually into the entire body of the other, two streams of them may be mixed,—in fact, I find this to be the most practical method.

The streams are first thoroughly mixed, and any gases that may be present at the reaction mixture are swept by a stream of air into an electrolytic cell in which the electrolyte is continually replaced. At each instant the conductivity in the cell corresponds to the condition of the reaction mixture a short time previously. For example, if there is a temporary excess of ammonia, the conductivity will temporarily increase. But as soon as the excess is corrected, the conductivity will drop off.

But the control gas need not be furnished by one of the main reagents. It may be present in just a small amount in admixture with one of said ingredients. For example, the following reaction evolves no gas at any stage:

But small amounts of ammonia may be added to either solution, and being a weak base will be evolved from the reaction mixture as soon as the alkali is in even slight excess.

Instead of an alkaline indicating gas, like ammonia, I may employ an indicating gas of an acid nature, such as sulfur dioxide, which is found to be remarkably effective in its rapid indication in the cell. For example, in the reaction between sulfuric acid and sodium hydroxide, the formulae of which are given above, a small amount of sodium sulfite may be added. The instant that the reaction mixture becomes acid, SO_2 is evolved, and being swept into the water of the detection cell, the latter instantly indicates that the acid stage of the reaction has been reached.

Not only has the method been found useful in ordinary reactions between acids and alkalies, but it is very useful in reactions between oxidizing and reducing substances, such as when titrating calcium oxychloride against a sodium thiosulfate solution, or a solution of potassium permanganate against a solution of sulfuric acid or acid sodium sulfite. Chlorine and bromine alter the conductivity of the water in the detection cell with satisfactory rapidity, as well as gases hereinabove mentioned.

While my method and apparatus are useful when the conductivity of the detection cell is merely used as an indication, I greatly prefer to use such cell in automatically regulating the proportions of the reagents in the reaction mixture. Particularly when titrating streams of liquid it is desirable to have the cell connected with apparatus which automatically increases or decreases the rate of flow of one reagent relative to the other into the mixing chamber.

I shall now refer in detail to one embodiment of my apparatus, in which my process may be carried out, but it will be understood that the invention is not restricted to the

details thus given, except as indicated in the appended claims. The first reagent 1 flows from the storage tank 2 through pipe 3 into preliminary mixing chamber 4 where it mingle with the other reagent 5. The latter comes from storage tank 6 through the flow regulator 7 and pipe 8. As shown in the drawing, it is preferable to have the stream of reagent 5 flow upwardly against the descending stream of reagent 1. Obviously any means of thoroughly mixing the reagents can be employed.

From the preliminary mixing chamber 4 the reaction mixture passes into final reaction chamber 9 where it passes downwardly in the form of spray and is finally drawn off through pipe 10 to any convenient storage vessel (not shown). In the top of the final mixing chamber 9 is a vertical descending pipe 11, the bottom of which is conveniently flared, as shown at 12. If air entering with the reagents from the preliminary mixing box 4 into chamber 9 is insufficient, a small air vent 111 may be provided in the side of chamber 9, but this is usually not necessary. The pipe 11 opens into a liquid separator chamber 13, the latter being connected with the lower part of chamber 9 by means of pipe 14. The separator 13 is connected by pipe 15 with the electrolytic detector cell 16. The latter receives its water or aqueous electrolyte through pipe 17, the entrance to which from the water supply is controlled by a needle valve 18 operated by handle 19. Below the valve 18 the pipe 17 is connected by pipe 20 with a suction device 21 which, as shown, may conveniently take the form of an aspirator or so-called water vacuum pump. The water from the aspirator passes into chamber 22 on its way to the discharge 23, and the supply of water for the electrolytic cell may be obtained from 22, as shown.

The detector cell 16 comprises two electrodes 24 connected by leads 25 with a circuit containing a solenoid 26 and a lamp 27. There may conveniently be arranged a switch 28 which is normally closed and leads 25 may be connected with a suitable source of either direct or alternating current. Within the solenoid 26 is a plunger 29 connected by a wire or link 30 with the arm 31 of the flow control 7.

The flow control comprises a cylindrical vessel 32 rotated about its horizontal axis in any suitable bearings within a tank or container 33. Vessel 32 is provided with radially extending discharge openings 34. The tank 33 is provided with a vertical partition 35 and one of the discharge openings 34 empties the liquid into that part of the tank 33 which is connected to the preliminary mixing chamber 4 through pipe 8. The other discharge opening 34 empties the liquid into that part of the tank 33 which is connected with the pipe 36, which may lead

to any suitable storage receptacle, not shown, or any return piping system for bringing the liquid back to storage tank 6. A spring 37 normally tilts the cylinder 32 in such a position that it produces the maximum discharge into the pipe 8, with little or no liquid passing out the other radial opening 34 to pipe 36. I have found that this cylinder control is a particularly useful one, because it is so easily tilted by the small force exerted by the solenoid 26 on plunger 29. It will be particularly noted that the flow through the radial openings 34 causes a mechanical reaction only radially, and consequently the out-flowing streams from cylinder 32 do not tend to rotate the latter,—in other words, do not interfere with the automatic regulation.

The water from the cell 16 passes by pipe 38 into the trapped pipe 39. From the junction of pipes 38 and 39 there is a connection 40 passing around the top of the cell to equalize the pressure.

Referring to Fig. 2 for further details of the stream regulator, it will be noted that the tank 33 is provided with observation windows 41 through which may be observed the radial openings 34. The axle 42 of the cylinder 32 rests in any suitable bearing 43 of minimum friction. Upward from the axle 42 is an extension 44 on the top of which is fastened the lever 31. The cylinder 32 is open at the top so that the descending liquid 5 from storage tank 6 may drop freely into it without any mechanical connection between said tank 6 and cylinder 32.

I shall now describe briefly the operation of this apparatus, in which my novel process is carried out. A solution of sulfuric acid is, for instance, charged into tank 2 and a batch of ammonia water is charged into tank 6. The acid and ammonia solutions meet and react with each other in the preliminary mixing box 4. Owing to spring 37, the cylinder 32 is in the position to feed enough neutralizing ammonia solution through pipe 8 to the mixing box. The reaction mixture then flows into the final reaction chamber 9 around the flared end of 12 of pipe 11.

The aspirator 21 being in operation and the valve 18 being properly regulated, there is a partial vacuum created in pipes 17, 15, 13 and 11 and yet drops of water pass downwardly by gravity through the pipe 17 into the cell 16. While the water might be conducted downwardly by a separate pipe from that through which the vacuum is transmitted, it has been found in actual practice that the creation of the vacuum does not interfere with the downward flow of the water drops.

If at any time the amount of ammonia water entering the preliminary mixing box 4 and flowing over the end of pipe 11 is in excess, ammonia gas will be present in the final reaction chamber 9 and will be drawn

by the vacuum through pipes 11 and 15 through the top of cell 16 into pipe 17, where it dissolves in the water descending to the cell. This electrolyte then flows through the cell 16 and outward through the pipes 38 and 39. As the electrolyte containing the ammonia passes between the plates 24, the resistance of the cell is greatly lessened and an increased current passes through the solenoid 26 and lamp 27. This pulls downwardly upon the soft steel plunger 29 and the wire 30, and consequently pulls downwardly on lever 31 and tilts the cylinder 32 against the action of spring 37 so as to lessen the flow of ammonia water in the pipe 8.

As soon as the excess of ammonia water is thus removed, and a normal balance in the titration reaction is obtained, no ammonia gas is drawn with the air through pipes 11 and 15 and consequently the water passing through the cell 16 has a much higher resistance. This causes the current through the solenoid 26 to be diminished and the spring 37 consequently rocks the cylinder 32 so as to increase the amount of ammonia water which passes into pipe 8 and thence to the reaction chambers. It will be noted that the lamp 27 not only serves as a resistance to lower the voltage at the solenoid terminals, but its brightness will indicate visually whether the conductivity of the cell 16 has been increased or decreased. After the apparatus is once started it maintains a properly balanced titration reaction without any attention, thus practically eliminating any labor cost and yet insuring exactly regulated results. While I have referred, for convenience, to a reaction between sulfuric acid and ammonia water, it will be understood that any suitable reagents, one of which supplies a gas to the reaction chambers, may be substituted, as hereinabove explained.

Having thus described my invention, what I claim as new and desire to secure by Letters Patent is:

1. In the process of regulating a chemical reaction, one stage of which causes the presence at the reaction mixture of a gas that will induce a characteristic conductivity in an electrolyte, the steps for finding whether said stage has been reached, which consist in mixing said electrolyte with any gas from said reaction mixture and then measuring the conductivity of said electrolyte, said electrolyte being separate from the reaction ingredients.

2. In the process of regulating a chemical reaction, one stage of which causes the presence at the reaction mixture of a gas that will induce a characteristic conductivity in an aqueous electrolyte, the step of detecting the reaching of said stage by removing any gas from said reaction mixture and mixing it with successive portions of said electrolyte and measuring the conductivities of said por-

- tions until said characteristic conductivity is found in one of them, said electrolyte being separate from said reaction ingredients.
3. In the process of regulating a chemical reaction in which the presence of a gas at the reaction mixture indicates an excess of one of the reagents, said gas having the property of inducing a characteristic conductivity in an aqueous electrolyte, removing any gas progressively from said reaction mixture and mixing it with successive portions of said electrolyte, measuring the conductivities of said portions, and when said characteristic conductivity is found, adjusting the relative proportions of the reagents to remove said excess, said electrolyte being separate from the reaction ingredients.
4. The process which comprises mixing streams of reagents to titrate them against each other, one of them supplying a gas at the reaction mixture when it is in excess, said gas having the property of inducing a characteristic conductivity in an aqueous electrolyte, removing any gas progressively from said reaction mixture and mixing it with a separate stream of said electrolyte, measuring the conductivity of said electrolyte at one portion of its travel, and adjusting the rate of flow of one of said streams of reagents relative to the other to remove said excess, whenever said characteristic conductivity is found in said electrolyte.
5. In apparatus for conducting chemical reactions, a fluid mixing chamber, means for feeding a stream of one reagent thereto, means for feeding a stream of a second reagent thereto for titrating with said first-named reagent, said second reagent supplying a gas in said chamber when present in excess, an electrolytic cell containing an aqueous electrolyte, the conductivity of which is changed by said gas, means for passing any of said gas from said chamber into said electrolyte to cause changes in the conductivity thereof and means including electrical devices connected with said cell for automatically regulating the rate of flow of one of said streams relative to the other in accordance with said changes in conductivity.
6. In automatic titrating apparatus, a fluid mixing chamber, means for feeding a stream of one reagent thereto, means for feeding a stream of a second reagent thereto for titrating with said first-named reagent, said second reagent, when in excess, supplying a gas in said chamber, an electrolytic cell through which a stream of aqueous electrolyte passes, the conductivity of which is changed when any of said gas enters said stream of electrolyte, means for passing any of said gas from said chamber into said stream of electrolyte to cause changes in the conductivity thereof and means for lessening the increasing the flow of said second reagent relative to the flow of the first reagent in accordance with the
- increase and decrease respectively of the conductivity of said stream of electrolyte.
7. In automatic titrating apparatus, a chamber in which the reagents are mixed, an electrolytic cell, means for renewing the electrolyte in said cell, a suction device connected with said cell and said chamber for drawing gas evolved in said chamber into contact with the electrolyte of said cell, a flow regulator for at least one of said streams of reagents, and means controlled by said cell for actuating said regulator.
